The ornamental design for an electronic device, as shown and described.

DESCRIPTION

FIG. 1 is a bottom front perspective view of an electronic device showing our new design;

FIG. 2 is a bottom rear perspective view thereof;

FIG. 3 is top front perspective view thereof;

FIG. 4 is top rear perspective view thereof;

FIG. 5 is a front view thereof;

FIG. 6 is a rear view thereof;

FIG. 7 is a bottom view thereof;

FIG. 8 is top view thereof;

FIG. 9 is a right side view thereof; and,

FIG. 10 is a left side view thereof.

The shade lines in the Figures show contour and not surface ornamentation.

The dashed lines in the Figures show unclaimed portions of the electronic device that form no part of the claimed design.
